UNITED STATES PATENT OFFICE.

JOSEPH H. MILLS, OF RICHMOND, INDIANA, ASSIGNOR TO RICHMOND CASKET COMPANY, OF RICHMOND, INDIANA, A CORPORATION OF INDIANA.

SCREEN FOR BURIAL-CASKETS.

1,175,005.

Specification of Letters Patent. Patented Mar. 14, 1916.

Application filed December 27, 1906. Serial No. 349,681.

To all whom it may concern:

Be it known that I, JOSEPH H. MILLS, a citizen of the United States, residing at Richmond, in the county of Wayne and 5 State of Indiana, have invented a certain new and useful Screen for Burial-Caskets, of which the following is a specification.

My invention relates to burial caskets and the object thereof is to provide a simple and 10 efficient shield or screen which is adapted to be applied or attached to the casket for use before and during the funeral for the purpose of not only concealing the exterior of the casket and its hardware as well as the 15 support or supports (ordinarily termed the casket carriage or pedestal), but also to decorate the same elaborately and with a wide range of style and character of decoration.

One of the chief objects of the provision 20 of this shield or screen is to enable a cheaper character or grade of casket to be employed with the same or even better effect and results than when burial caskets of the higher 25 grades and with more expensive trimmings are used, thereby enabling those who cannot afford the high-priced caskets the same effects at a much less expense instead of being, in fact, compelled to buy a casket whose price is beyond their means.

It will be understood that the shield or 30 screen forms no part of the burial outfit, but is used by the undertaker to conceal caskets and the space below them as above explained and to provide surrounding decoration and 35 adornment necessary to overcome the harshness of the usual conditions. Moreover, the shield or screen is provided with means for attachment and detachment whereby it may be used over and over again. As a result 40 of the use of my screen, it is thus possible to employ a cheaper grade of burial casket and also to dispense with the necessity of carrying in stock the considerable number (now required) of different styles and 45 grades of casket in different shades of color. Furthermore, my screen is so made and arranged that it may be applied or adjusted to any size of casket and may also be attached to and detached from the casket with 50 great facility as is necessary under its peculiar conditions of use.

In the drawings, Figure 1 is a side elevation of a casket with my screen attached thereto; Fig. 2 a section on the line 2--2 55 of Fig. 1; Fig. 3 a similar section but

showing one of the sides let down to convert the casket into the couch form; Fig. 4 a perspective of one of the side sections of the screen when the latter is made in sections; Fig. 5 a perspective of one of the end 60 sections of the screen; and Fig. 6 a detail view on an enlarged scale of the upper edge or margin of the screen showing the hooks for attaching the screen to the casket.

My invention relates, as hereinbefore 65 stated, to the provision of the screen structure hereinafter described for concealing the casket proper, as well as the supports or pedestal and also for providing a surrounding decoration. This screen is so made that 70 it may be applied to different types of burial casket with the necessary changes or adjustments occasioned by the particular construction of the casket. In the present instance, I have shown my screen applied to 75 three different types or classes of burial casket, as will be apparent from the description hereinafter given. However, I will first describe my invention as applied to a burial casket of the usual character and one having 80 a removable lid or cover as illustrated in Fig. 1.

Referring more particularly to Figs. 1, 2, 4, 5 and 6, my screen comprises in the present instance a fabric which is, by preference, 85 made in four different sections, two similar side sections 1, and two similar end sections 2, the side sections being positioned along the opposite sides of the casket and suspended or draped therefrom and the end sections 90 being similarly suspended or draped from the casket. This screen, however, might be made in one single or continuous piece, although in practice I have found that it is more convenient to make the fabric in sections as shown, besides which the range of 95 use of any one screen is considerably increased by such division into sections.

It will be understood that the screen may be made of any suitable material or fabric 100 and also that the same may be suitably figured. In practice an undertaker may provide himself with several of these screens of different colors or shades of color or with different figure or pattern.

Describing the particular construction and arrangement of screen shown in Figs. 1, 2, 4, 5 and 6, I provide the upper edge of each of the sections with a hem, through 110 which cords are passed, the side sections

having the cords 3 and the end sections the cords 4. The adjacent ends of the respective cords are in practice tied together and the same, with their depending tassels, form a part of the decorative effect of the screen. In applying the screen to the casket and fitting or adjusting the same thereto, the goods or fabric is gathered along the cords and the proper draping effect also thereby obtained. The upper margin of the fabric, together with the cords, is positioned on the inner side of the walls of the casket and slightly below the top edge thereof, with the result that the screen may thereby be held in place. However, I do not care to depend entirely upon this arrangement for thus holding the screen in place, but prefer to provide means for positively holding the same against any possibility of displacement or derangement.

Different means may be provided, but for the purpose of enabling the undertaker to quickly and readily attach and detach the screen, I provide the upper edge or margin 25 of the screen with hooks such as the hooks 5 illustrated in detail in Fig. 6. These hooks are arranged on the inner side of the upper edge or hem of the fabric so that they readily engage with the upholstering 30 of the casket when the screen is in place and at the same time the hooks are concealed from view. By preference, for the purpose of securing a proper draping of the side sections, I provide on the inner side of such 35 side sections and intermediate their height a strip of elastic or webbing 6, suitably connected or attached to each side section and having means of attachment to the end portions of the casket as illustrated in Fig. 1. 40 For this purpose, the ends of the webbing may be provided with eyes and the end portions of the casket with pins or buttons 7.

My screen may also be applied to the couch type of burial casket, as illustrated 45 in Fig. 3, wherein one side 8 of the casket, which is hinged, is let down with the result that the end sections of the screen will conceal the ends of the casket as before, as well as the ends of the side wall 8, while the 50 side section of the screen, which falls or drapes below the lower edge of the side wall 8 in its let-down position, will conceal the space therebelow, and will constitute the drapery and decoration thereat, all as clearly 55 illustrated in Fig. 7. When the screen is employed on a casket of this particular type it is only necessary for the side sections to drape the space below the lower edge of the side wall 8 when in its let-down position, 60 but as the sections of the screen are standard and applicable to all types of caskets, I

prefer to use the sections as hereinbefore described and attach the same, particularly the side section belonging to the hinged side wall 8 and to attach the same to the upholstery thereof, with the result that such side section will be in two folds or thicknesses as to the portion thereof concealed behind the side wall 8, as clearly illustrated in Fig. 3.

In the two types of burial caskets hereinbefore described, the casket is screened all the way around, but in that type of casket which is provided with a hinged top or cover one of the side sections may, if desired, be dispensed with. This side section 70 would be the one adjacent the side wall to which the top or cover is hinged, inasmuch as this side of the casket is not exposed to view in the use of this particular type. My screen is obviously applicable as well to 75 the type having a hinged side but with a hinged lid.

I claim:

1. A screen for concealing the exterior of a burial casket and providing a decoration 85 comprising separate sections or pieces of fabric arranged to be attached to and draped from the casket, a side section having a strip in its inner side intermediate its height and arranged to be removably attached at its ends to the casket.

2. A screen for concealing the entire exterior of a burial casket as well as the usual supports therefor, such screen comprising separate sections of fabric, and separate 95 cords on which the upper edges thereof are gathered, said cords being adapted to be positioned within the top edge of the casket to hold the fabric in place and the ends of the cords being draped for decorative effect. 100

3. A screen for concealing the entire exterior of a burial casket as well as the usual supports therefor for providing a decoration comprising separate sections or pieces of decorated fabric having hems on their 105 upper edges, and separate cords in the hems, said cords being adapted to be positioned within the top edge of the casket to hold the fabric in place and the ends thereof being exposed and draped for decorative effect. 110

4. In combination with a burial casket of the type having a hinged side arranged to be swung downwardly, a screen concealing the exterior of such casket comprising a fabric whose portion adjacent the hinged side is attached thereto, and means for attaching the screen to the stationary ends of the casket.

JOSEPH H. MILLS.
